(57) **CLAIM**

The ornamental design for an oil pan as shown and described.

DESCRIPTION

FIG. 1 is a first perspective view of an oil pan, showing our new design;

FIG. 2 is a second perspective view of the oil pan of FIG. 1;

FIG. 3 is a front view of the oil pan of FIG. 1;

FIG. 4 is a rear view of the oil pan of FIG. 1;

FIG. 5 is a first side view of the oil pan of FIG. 1;

FIG. 6 is a second side view of the oil pan of FIG. 1;

FIG. 7 is a top view of the oil pan of FIG. 1; and,

FIG. 8 is a bottom view of the oil pan of FIG. 1.

The broken lines shown in the drawings are included for the purpose of illustrating the unclaimed portions of the oil pan.

The broken lines form no part of the claimed design.

1 Claim, 8 Drawing Sheets
